INVENTOR:

Edward E. Gold,
By his Attorneys,

Arthur G. Fraser # UNITED STATES PATENT OFFICE.

EDWARD E. GOLD, OF NEW YORK, N. Y.

DESIGN FOR A FRONT PLATE FOR ELECTRIC HEATERS.

SPECIFICATION forming part of Design No. 29,891, dated December 27, 1898.

Application filed October 25, 1898. Serial No. 694,555. Term of patent 14 years.

To all whom it may concern:

Be it known that I, EDWARD E. GOLD, a citizen of the United States, residing in the city, county, and State of New York, have invented a certain new and Original Design for the Front Plate of an Electric-Heater Casing, of which the following is a specification.

This is a design for the front plate of an electric-heater casing.

Figure 1 of the drawings is a front elevation thereof, and Fig. 2 is a transverse section on the line 2 2.

The plate A has two open-work panels B B, separated by a plain band *a* and surrounded 5 exteriorly by plain marginal portions *b b*. Each panel is surrounded by a rib *c*, while within this rib it is subdivided by cross-bars in the manner shown, so as to form oblique square openings *e e'*, surrounded by pointed

oblong openings *d d*, which latter are reduced to mutilated openings *ff* on the sides next the bounding-rib *c*. The general effect is that of large squares, of which one is marked

15 C, having their corners cut off and extended in a row along the middle of each panel, each of these large squares being subdivided by the arrangement of the oblique small square *e* in

the middle and by bars extending horizontally and vertically from the corners of the middle oblique square to the bounding-ribs 30 of the large square C, so that the portion of the latter exterior to the central square *e* is cut into four openings *d d*, having parallel sides and pointed ends, while the cut-off corners of the large squares C constitute two 35 sides of oblique squares *e' e'*, the outer corners of which extend to the marginal rib *c*, the spaces between each two smaller squares *e' e'* being filled by the two mutilated openings *ff*. The bars or gratings by which the 40 panels B B are cut up to form the openings *e e' d f* are lettered *g*.

I claim—

The design for the front plate of an electric-heater casing substantially as hereinbefore described and shown. 45

In witness whereof I have hereunto signed my name in the presence of two subscribing witnesses.

EDWARD E. GOLD.

Witnesses:

FRED WHITE,
THOMAS F. WALLACE.
